WIDE BAND AMPLIFIER AND MODULATION SYSTEM

Harold A. Wheeler, Great Neck, N. Y., assignor to
Hazeltine Corporation, a corporation of Delaware

Application August 16, 1938, Serial No. 225,147

14 Claims. (Cl. 179—171.5)

This invention relates generally to improved arrangements for amplifying a wide band of frequencies and particularly to such arrangements utilizing a plurality of vacuum tubes coupled in parallel in one or more stages thereof to secure greater amplification per stage and greater amplifying efficiency. The invention is of particular utility in coupling a low-pass signal-translating channel to a band-pass signal-translating channel by means of a plurality of modulator tubes operating in parallel.

Dead-end filters having one or more pairs of terminals and having a full-shunt or full-service reactance termination at one end thereof have been utilized to maintain a predetermined value of transfer impedance substantially uniform over a wide band of frequencies across one or more pairs of terminals of a coupling network. The principles and theoretical relations underlying dead-end filters of this type may be described most simply by reference to a nondissipative wave filter of the constant- k type. Such a filter may be assumed to have an infinite number of sections or to consist of a finite number of sections terminated with its image impedance to procure the same characteristics. The input impedance of such a filter is uniform over the pass band if the input termination is full-shunt or full-series, as distinguished from the usual mid-shunt or mid-series termination. The input impedance is the iterative impedance measured in parallel with a full-shunt arm or in series with a full-series arm, as distinguished from the conventional image impedance measured at mid-shunt or mid-series. This input impedance may be utilized as a two-terminal coupling impedance, the remainder of the filter serving merely as a passive dead-end supplementary network utilized to build up the desired uniform impedance.

For example, any such filter of finite total band width can be arranged to include as its full-shunt arm a capacitance of the value $C=2/R\Delta\omega$, in which R is the mid-band image impedance and $\Delta\omega$ is the total width of the pass band in radians per second. The uniform full-shunt iterative impedance across the capacitance C has the magnitude $R=2/C\Delta\omega$. This relationship expresses the theoretically maximum value of impedance that can be maintained across the capacitance C throughout frequency bands of total width $\Delta\omega$. In the case of a simple low-pass filter, the value of R is twice the reactance of the capacitance C at the cutoff frequency.

The dead-end filter may be utilized also as a four-terminal network, that is, a filter comprising

an active portion and a confluent portion. In general, each of the dead-end terminal devices connected to the filter is limited in performance, over a wide frequency band, by either shunt susceptance or series reactance. Four-terminal networks may be employed which utilize the above-recited principles for maintaining a predetermined uniform impedance across shunt susceptance, or a predetermined uniform admittance through series reactance, over a wide band of frequencies. The total susceptance or reactance of the circuits to be coupled is divided into smaller component portions connected in different sections of a filter, so that the impedance or admittance of the filter is limited, not by the total, but by the greatest indivisible portion of the undesired reactance or susceptance. Coupling networks of this general type are described and claimed in applicant's copending applications, Serial No. 203,595 filed April 22, 1938, Patent No. 2,167,134, July 25 1939 and No. 203,596, filed April 22, 1938, Patent No. 2,167,135, July 25, 1939. Two terminal networks using similar principles are described and claimed in applicant's copending applications Serial No. 203,597 filed April 22, 1938, Patent No. 2,167,136, July 25, 1939 and No. 203,598 filed on April 22, 1938, Patent No. 2,167,137, July 25, 1939. Certain of the prior art disclosures utilizing a network of the type under discussion, however, have been such as to require an appreciable amount of power to be dissipated in the dead-end termination of the filter; for example, it has been proposed to operate several tubes in parallel, their input and output terminals being staggered along input and output dead-end filters so that only the capacitance of one set of terminals of each tube limits the impedance of each filter section. The total phase shift of each section of the filters is such that, when the signal carrier wave has a frequency equal to the mid-frequency of the pass band of the filter, so that the major portion of the power is concentrated in the middle of the pass band, the major portions of the currents delivered to the dead-end termination of the output filter by the several parallel tubes are in phase and maximum power is dissipated therein.

Dead-end filters having a plurality of pairs of terminals have also been utilized in arrangements for coupling a band-pass signal-translating channel of a modulated-carrier signal-translating system to a low-pass signal-translating channel. For example, it has further been proposed to operate a plurality of vacuum-tube detectors in parallel between a band-pass car-

rier-frequency signal-translating channel and a low-pass modulation-frequency signal-translating channel, each of the channels comprising as a coupling network a dead-end filter having a plurality of pairs of terminals. Arrangements of the prior art, however, have been such that the phase-shift frequency characteristic of the low-pass signal-translating channel has been, over the pass band, of a slope similar to that of the band-pass signal-translating channel only where the low-pass band was half the width of the band-pass band, as for double-sideband operation.

It is an object of the invention, therefore, to provide a new and improved coupling network comprising shunt capacitance across which there is maintained a maximum and preferably uniform value of transfer impedance over a wide band of frequencies and in which useless dissipation is minimized.

It is another object of the invention to provide an amplifier utilizing a dead-end filter of the type described having a full-shunt termination at the active end thereof, in which the dead-end losses are a minimum.

It is a further object of the invention to provide a wind-band carrier-frequency translating system comprising a dead-end filter as a coupling network, in which the carrier frequency is so related to the pass band of the filter that the dead-end losses in the filter are a minimum.

It is still another object of the invention to provide a wide-band signal-translating system comprising a low-pass signal-translating channel coupled to a band-pass signal-translating channel including a dead-end filter coupling network, in which the pass bands of the two channels are equal and the phase-shift frequency characteristics of the two channels are similar over the pass band.

In accordance with a preferred embodiment of the invention, there is provided in a modulated-carrier signal-translating system a signal-translating channel adapted to be energized by a source of carrier-frequency signals and including input and output circuits, a coupling network comprising a dead-end filter having a resistance termination at its dead end. Each of the above-mentioned input and output circuits is coupled with the filter at a junction of the filter separated from the dead end by at least one half-section of the filter. The carrier frequency of the source is located substantially at one edge of and within the pass band, whereby the carrier-frequency component is not substantially attenuated between the input and output circuits, while the carrier-frequency component is substantially attenuated between the input circuit and the resistance termination.

Also in accordance with a preferred embodiment of the invention, there is provided in a modulated-carrier signal-translating system, a signal-translating channel including a plurality of phase-displaced input circuits and an output circuit. The channel includes a coupling network comprising a dead-end filter having a resistance termination at its dead end and the above-mentioned input circuits are coupled with the filter at electrically-spaced junctions thereof remote from the dead end. The output circuit is coupled to the filter at a point more remote from its dead end than the above-mentioned junctions, whereby respective paths through successive input circuits to said output circuit include a decreasing number of sections of the filter and successive

paths from the input circuits to the output dead-end resistance include an increasing number of sections of the filter. The carrier frequency of the system is located within the pass band of the filter and so related with the transfer characteristics of the filter that minimum power is dissipated in the above-mentioned dead-end resistance termination.

Also, in a preferred embodiment of the invention, input and output dead-end filter networks are utilized in low-pass and band-pass signal-translating channels, respectively, between which are coupled a plurality of vacuum tubes operating in parallel. The dead-end filters are so designed that the signal-translating channels comprising the dead-end filters have similar phase-shift frequency characteristics and equal band-widths; that is, over the pass band of the system, each of the signal-translating channels has the same total phase shift and band-width, so that the slopes of the phase-shift frequency characteristics are nearly the same in the two channels.

For a better understanding of the invention, together with other and further objects thereof, reference is had to the following description taken in connection with the accompanying drawings and its scope will be pointed out in the appended claims.

Fig. 1a of the drawings shows an embodiment of the invention utilizing a plurality of vacuum tubes in parallel as a coupling between band-pass signal-translating channels; Fig. 1b shows the phase-shift frequency characteristic of the system of Fig. 1a; Fig. 2a illustrates an embodiment of the invention utilizing a plurality of vacuum-tube modulators as a coupling between a low-pass signal-translating channel and a band-pass signal-translating channel; Fig. 2b illustrates the phase-shift frequency characteristics of the signal-translating channels of Fig. 2a; Fig. 2c represents certain characteristics of the system of Fig. 2a when the carrier frequency is located at one edge of the pass band of the band-pass channel; Fig. 2d illustrates certain characteristics of the circuit of Fig. 2a when the carrier frequency is located in the center of the pass band of the band-pass signal-translating channel; and Fig. 3 illustrates another embodiment of the invention in a band-pass channel.

Referring now more particularly to Fig. 1a, there is shown a band-pass modulated-carrier signal-translating system comprising three stages of amplification including vacuum tube 10 in the first stage, tubes 11 and 12 coupled in parallel in the second stage, and tube 13 in the third stage. The system has a pair of input terminals 14 and a pair of output terminals 15. Dead-end filters, using the principles described in detail in the above-mentioned copending applications, are utilized to couple the output circuit of vacuum tube 10 to the input circuits of vacuum tubes 11 and 12 and to couple the output circuits of vacuum tubes 11 and 12 to the input circuit of vacuum tube 13. These filters are designated generally as 16 and 17, respectively. Each of the filters 16 and 17 effectively comprises a plurality of modified constant- k sections, an m -derived section, and a resistive terminating impedance which matches the image impedance of the m -derived section over the pass band of the system. Certain inductances of filters 16 and 17 have been replaced by equivalent transformer elements and the interelectrode capacitances of tubes 10, 11 and 12 provide mid-shunt capacitances for the filters at the junctions to which they are connected, as

indicated by the dotted-line condensers. Thus, filter 16 comprises transformers 20, 21 and 22 which comprise the equivalent inductance elements of the modified constant- k filter sections while transformer 23 provides the equivalent inductance elements for the m -derived section of the filter, the image resistance of which is matched over the pass-band by resistance element 24. The remaining shunt inductances of filter 16 are inductances 25 and 26, while the shunt condensers of the filter are 27, 28, 29, 30, 31 and 32.

The output filter 17, utilized for coupling the output circuits of tubes 11 and 12 to the input circuit of tube 13, is generally similar to filter 16 with the additional feature that an intermediate shunt element included in inductance 39 and condenser 45 is provided as a termination for filter 17 at the active end thereof, in a manner described and claimed in the above-mentioned copending applications. Thus, filter 17 includes transformers 33, 34 and 35, the windings of which provide equivalent inductance elements for modified constant- k sections, and transformer 36, the windings of which provide equivalent inductance elements for an m -derived section having an image impedance which is approximately matched over the pass band of the system by resistor 37. The remaining inductances of filter 17 are shunt inductances 38 and 39. The shunt condensers of filter 17 are designated 40, 41, 42, 43, 44 and 45. In one embodiment of the invention, the circuit may be utilized with a single tube 12, tube 11 being omitted from the circuit.

In Fig. 1b, there is shown the phase-shift frequency-characteristic of each of the modified constant- k filter sections of filters 16 and 17, each filter having a total phase shift over the pass band of π , instead of 2π , as in conventional constant- k sections.

Considering now the operation of the circuit of Fig. 1a, the carrier-frequency power translated from the two tubes 11 and 12 to the dead-end resistor 37 of the output filter 17 cancels out if the carrier frequency is in the middle of the pass band. This is apparent when separate paths from input terminals 14 through tubes 11 and 12 to resistor 37 are considered. Specifically, tubes 11 and 12 are coupled to filter 17 at electrically-spaced junctions thereof remote from the dead end of the filter which includes resistor 37, while the output terminals 15, 15 of filter 17 are more remote from its dead end than the junctions to which tubes 11 and 12 are coupled. The signal passing through tube 12 to resistor 37 travels through two more filter sections than the signal through tube 11. Since each section of the filter has a phase shift of $\pi/2$ in mid-band, the relative displacement of the carrier-frequency currents translated to resistor 37 through the two paths is π , so that the carrier-frequency power tends to cancel out; that is, respective paths through successive input circuits to filter 17 to the output terminals 15, 15 thereof include a decreasing number of sections of the filter, while successive paths from the input circuits to the output dead-end resistance 37 include an increasing number of sections of the filter 17. Since filter 17 is terminated at its active end to provide a maximum impedance over a wide range of frequencies across the active terminals thereof, as described in the above-mentioned copending applications, the filter is not ideally terminated, resulting in some reflection at the active end, so that there is not an exact cancellation of power at the carrier frequency in resistor 37.

It will be understood that any number of additional sections may be provided for filters 16 and 17 or that more than two tubes, connected in the manner shown, can be coupled between succeeding junctions of the filters. Furthermore, while in the arrangement described there results a cancellation of power at the carrier frequency in resistor 37 as between parallel-connected tubes 11 and 12, it will be understood that if an odd number of tubes is utilized, cancellation of power at the carrier frequency will result only if the carrier frequency is displaced slightly from the mid-frequency of the system.

Furthermore, the sections of the input and output filters may have any given phase-shift characteristic over the pass-band of the system and the carrier frequency may be so located with respect to the phase-shift frequency characteristics that cancellation of the power at the carrier frequency in the dead-end resistor 37 of the filter 17 results.

The system of Fig. 1a may be utilized in another way to minimize carrier dissipation in dead-end resistor 37 of the filter 17; that is, by operating the system with the carrier frequency near the edge of the pass band, as would be done with single side-band operation. The m -derived termination, for which the windings of transformer 36 provide the inductive elements, places a relatively high reactance in series with the dead-end resistor 37 (or a relatively low reactance in shunt therewith) at frequencies near the edge of the pass band. Therefore, locating the carrier frequency near the edge of the band greatly reduces the carrier power dissipated in resistor 37. The system just described may, of course, be operated with only one tube coupled between filters 16 and 17. Where several tubes are employed, a carrier frequency slightly within the band may be chosen, at which all carrier power cancels out by virtue of the first relations discussed above, and the cancellation is non-critical because of the reduced carrier power in resistor 37 at frequencies near the edge of the band. These benefits are secured regardless of whether an even number or an odd number of tubes are utilized in parallel.

In Fig. 2a there is shown a system similar in many respects to that of Fig. 1a. The system of Fig. 2a is utilized to couple a low-pass channel, through parallel-operating modulator tubes, to a band-pass channel of the system. The system thus comprises a first stage including a vacuum tube 18, a second stage, including parallel-operating modulator tubes 11' and 12', and a third stage including a vacuum tube 13. The band-pass output filter 17 of Fig. 2a is identical with that of Fig. 1a and corresponding circuit elements have been given similar reference numerals in the two figures. The input filter 50 is of the low-pass type and comprises three constant- k sections including series inductance arms 51, 52 and 53 and shunt capacitance arms 54, 55, 56 and 57, capacitance elements 54, 55 and 56 being shown in dotted lines to indicate that they are comprised in whole or in part of the inherent inter-electrode capacitances of the vacuum tubes coupled to the filter at these points. An m -derived half-section including an inductance 58 and a capacitance 59 is provided for filter 50. The image impedance of the m -derived half section is approximately matched over the pass band of the system by terminating resistor 60. There are provided input terminals 61 for the low-pass section of the circuit and input terminals 62 for the band-pass section. The modulation-frequency signals 75

supplied to terminals 61 modulate the carrier-frequency signals applied to terminals 62, in the parallel-operating tubes 11' and 12', to provide a modulated-carrier signal which is coupled to output terminals 15 through the output filter 17. The input circuit coupled to input terminals 62 comprises a condenser 64 connected in parallel with inductances 65 and 66. Inductances 65 and 66 are inductively coupled to inductances 67 and 68 of the input circuits of vacuum tubes 11' and 12', respectively. The carrier-frequency input to modulators 11' and 12' is applied with such polarity that the carrier-frequency outputs of the modulator tubes are coupled in the same phase to output terminals 15.

The circuit of Fig. 2a effectively provides an arrangement in which the slope of the phase-shift frequency characteristic of the low-pass input filter 50 is approximately similar over the pass band to that of output filter 17. These characteristics are shown in Fig. 2b wherein curve A represents the phase-shift frequency characteristic of filter 50 and curve B represents the phase-shift frequency characteristic of filter 17.

If only one sideband is to be employed in the arrangements of the invention, it is preferable to locate the carrier at one edge of the pass band, in which case it is desirable that the relative phase shift of the band-pass filter over the pass band should be the same as that of the low-pass filter. This arrangement, in which the low-pass band width is equal to the band-pass band width and in which the relative phase shift over each pass band is π per section in each of filters 50 and 17, gives approximately the correct phase relations between the modulation-frequency signal and the modulation sideband signal components, regardless of where the carrier-frequency is located in the band. The carrier frequency must be near the edge of the band, however, if the band-pass filter is to accommodate a width of sidebands as wide as the band width of the low-pass filter. These characteristics are indicated in Figs. 2c and 2d wherein Fig. 2c illustrates the arrangement in which the carrier frequency is located at the low-frequency edge f_5 of the pass band f_5 , f_6 of the band-pass filter 17. The pass band of the low-pass filter 50 is indicated by O— f_7 . Fig. 2d illustrates a low-pass band width 50 of O— f_8 and a band pass from f_9 — f_{10} with the carrier frequency located at f_{11} , the mid-point of pass band f_9 — f_{10} . Due to the difference between curves A and B of Fig. 2b, the desired relation between the phase-shift frequency characteristic of input filter 50 and that of the output filter 17 of Fig. 2a is not exact but is sufficiently close if the number of tubes in parallel between the filters is not too great, for example, not greater than four.

In Fig. 3, there is illustrated a modification of the circuit of Fig. 1a in which the single tube of each of the parallel channels is replaced by a driver tube and a power tube. Similar circuit elements in the two figures have been given 65 identical reference numerals, the input filter 16 being identical with that of Fig. 1a. The output filter 70 is similar to output filter 17 of Fig. 1a except for the termination thereof at the active end. Output filter 70 is terminated to provide 70 an image impedance at output terminal 75 which matches the image impedance of a uniform transmission line. Tubes 11 and 12 of Fig. 1a have been replaced in the circuit of Fig. 3 by identical parallel channels each including a driver 75 tube 76, the input circuit of which is coupled to

filter 16 in the manner above described, and a power tube 77, the output circuit of which is coupled to output filter 70 in a manner similar to that described for coupling the output circuits of tubes 11 and 12 of Fig. 1 to the output circuit of filter 17. The output circuits of tubes 76 are coupled to the input circuits of tubes 77 by dead-end coupling filters in accordance with the disclosures of the above-mentioned copending applications. Each of these filters comprises a plurality of modified constant- k sections, the inductance elements of which are provided by the windings of a transformer 78 and shunt inductance arms 79 and 80, and an m -derived half-section, the inductance elements of which are provided by the windings of a transformer 81. Shunt capacitance arms 83, 84, 85 and 86 are provided for the filters, condensers 85 and 86 being shown in dotted lines to indicate that they are comprised in whole or in part of the inherent 20 interelectrode capacitances of tubes 76 and 77, respectively. The dead-end terminating resistor 87 of the coupling filter matches the image impedance of the m -derived half-section comprising transformer 81, while terminating resistor 88 is provided for the active end of the filter, being shown in dotted lines to indicate that it may be comprised of the inherent conductance of the circuit shown.

The circuit of Fig. 3 operates in a manner generally similar to that of Fig. 1a and a detailed explanation of its operation is deemed to be unnecessary. The circuit is a particularly advantageous arrangement for the power output circuit of a transmitter, inasmuch as relatively small driver tubes 76, 76 can be utilized together with relatively large power tubes 77, 77. Power tubes are generally operated by driving the grids positive, in which case the grid loading operates as a shunt conductance at the end of the coupling filter between the driver and power tubes. Therefore, conductance 88 may be proportioned in accordance with the disclosure of above-men- 35 tioned copending application, Serial No. 203,595.

It will be seen that, inasmuch as filter 70 is 45 adapted to be ideally matched with a uniform line coupled to terminals 75, there is no reflection if the line is properly terminated at the other end. Cancellation of power in the dead-end terminating resistor 87 of filter 70 is then more exact 50 than that obtained in dead-end resistor 37 of output filter 17 of Fig. 1a.

It will be understood that the above-described carrier-frequency amplifier arrangements are particularly advantageous when employed in push-pull amplifiers, there being no difference in the principles involved so that detailed explanation thereof is deemed unnecessary. Furthermore, it will be understood that it is preferable to utilize tubes in the above circuits which have an 60 anode resistance much higher than the impedance of the associated anode circuits whereby the signal voltage output of the tubes is minimized. This result is best obtained by using screen-grid tubes or high-mu triodes. If the tubes utilized 65 do not have a screen grid, the grid-anode coupling capacitance should preferably be neutralized. The most perfect type of neutralization and, therefore, the one which is preferred is the cross-neutralization of two tubes in push-pull re- 70 lation in the same signal channel. Each of the parallel channels should be neutralized individually regardless of the number of tubes utilized in the same channel.

While there have been described what are at 75

present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

10. 1. In a modulated-carrier signal-translating system, a signal-translating channel adapted to be energized by a source of carrier-frequency signals and including input and output circuits, a coupling network comprising a dead-end filter 15 having a resistance termination at its dead end, each of said input and output circuits being coupled with said filter, at a junction of said filter separated from said dead end by at least one half-section of said filter, the carrier frequency 20 of said source being located substantially at one edge of and within the pass band, whereby the carrier-frequency component is not substantially attenuated between said input and output circuits while the carrier-frequency component is 25 substantially attenuated between said input circuit and said resistance.

2. In a modulated-carrier signal-translating system, a signal-translating channel adapted to be energized by a source of carrier-frequency 30 signals and including input and output circuits, a coupling network comprising a dead-end filter having a resistance termination at its dead end, each of said input and output circuits being coupled with said filter at a junction of said filter 35 separated from said dead end by at least one half-section of said filter, said dead-end filter having an m -derived image impedance approximately matched by said resistance termination at its dead end, the carrier frequency of said source 40 being located substantially at one edge of and within the pass band, whereby the carrier-frequency component is not substantially attenuated between said input and output circuits while the carrier-frequency component is substantially 45 attenuated between said input circuit and said resistance.

3. In a modulated-carrier signal-translating system, a signal-translating channel adapted to be energized by a source of carrier-frequency 50 signals and including input and output circuits, said output circuit comprising appreciable shunt capacitance tending to limit the response thereof over a wide frequency range, a coupling network comprising a dead-end filter having a resistance 55 termination at its dead end, said filter including said capacitance as a mid-shunt element thereof, each of said input and output circuits being coupled with said filter at a junction of said filter separated from said dead end by at least one-half section of said filter, said dead-end filter 60 having an m -derived image impedance approximately matched by said resistance termination at its dead end, the carrier frequency of said source being located substantially at one edge of and within the pass band, whereby the carrier-frequency component is not substantially attenuated between said input and output circuits while the carrier-frequency component is substantially 65 attenuated between said input circuit and said resistance.

4. In a modulated-carrier signal-translating system, a signal-translating channel including two phase-displaced input circuits and an output circuit, a coupling network comprising a dead-end filter having a resistance termination

at said dead end, said input circuits being coupled with said filter at electrically spaced junctions thereof remote from said dead end, and said output circuit being coupled to said filter at a point more remote from its dead end than said junctions, whereby respective paths through successive input circuits to said output circuit include a decreasing number of sections of said filter and successive paths from said input circuits to said output dead-end resistance include 10 an increasing number of sections of said filter, and the carrier frequency being located within the pass band of said filter and so related with the transfer characteristics of said filter that minimum power is dissipated in said dead-end 15 resistance termination.

5. In a modulated-carrier signal-translating system, a signal-translating channel including input and output circuits, input and output dead-end filters, a plurality of vacuum tubes effectively 20 in parallel and coupling said circuits through portions of said filters, each of said filters having a dead-end resistance termination, said tubes being coupled with each of said filters at electrically spaced junctions thereof remote from 25 said dead ends, each of said input and output circuits being coupled with its respective filter at a point more remote from its dead end than the said junctions to which said tubes are coupled, whereby the respective paths from said input to 30 said output circuits through successive tubes include increasing numbers of sections of one of said filters and a decreasing number of sections of the other filter and the respective paths from said input circuit to said output dead-end resistance through successive tubes include an increasing number of sections of both of said filters, and the carrier frequency being located within the 35 pass band of said filters and so related with the transfer characteristics of said filters that minimum power is dissipated in the said dead-end resistance termination of the said output filter.

6. In a modulated-carrier signal-translating system, a signal-translating channel including input and output circuits, a coupling network comprising a dead-end filter having a resistance 40 termination at its dead end, a plurality of vacuum tubes effectively in parallel and coupling said circuits through portions of said filter, said tubes being coupled to said filter at electrically spaced 45 junctions thereof remote from said dead end, said junctions being displaced along said filter by portions each having predetermined phase shift at a predetermined frequency within the pass band of said system, said output circuit being coupled 50 with said filter at a junction of said filter more remote from said dead end than the junctions to which said tubes are coupled, whereby the respective paths from said input to said output circuit through successive tubes include decreasing 55 numbers of sections of said filter and the respective paths from said input circuit to said output dead-end resistance through successive tubes include increasing numbers of sections of said filter, and the carrier frequency of said system being proportioned with respect to said predetermined frequency so that the total phase displacement through successive tubes from said input circuit to said dead-end resistance at said carrier frequency differ by 180 degrees, whereby 60 carrier frequency power therein tends to cancel out.

7. In a modulated-carrier signal-translating system, a signal-translating channel including input and output circuits, input and output band- 75

- pass dead-end filters, a plurality of vacuum tubes effectively in parallel and coupling said circuits through portions of said filters, each of said filters having a dead-end resistance termination, said tubes being coupled to said filters at electrically spaced junctions thereof remote from said dead ends, said junctions being displaced along said filters by portions each having a 90 degree phase shift at a predetermined frequency within the pass band of said system, said input and output circuits being respectively coupled with said filters at junctions of said filters more remote from said dead ends than the junctions to which said tubes are coupled, whereby the respective paths from said input to said output circuits through successive tubes include increasing numbers of sections of one of said filters and a decreasing number of sections of the other filter, the respective paths from said input circuit to said output dead-end resistance through successive tubes including an increased number of sections of both of said filters, and the carrier frequency of said system being equal to said predetermined frequency whereby the total phase displacements through successive tubes from said input circuit to said output dead-end resistance at said carrier-frequency, differ by 180 degrees, so that the carrier-frequency power therein tends to cancel out.
8. In a modulated-carrier signal-translating system, a signal-translating channel including input and output circuits, input and output band-pass dead-end filters, an even number of vacuum tubes effectively in parallel and coupling said circuits through portions of said filters, said filters each having a dead-end resistance termination, said tubes being coupled with said filters at junctions of said filter separated from said dead ends, said junctions being electrically displaced along each filter by portions having zero to 180 degrees phase shift over the pass band of said system, said input and output circuits being respectively coupled with the said filters at junctions of said filters more remote from said dead ends than the said junctions to which said tubes are coupled, whereby the respective paths from said input to said output circuit through successive tubes include increasing numbers of sections of one of said filters and a decreasing number of sections of the other of said filters, the respective paths from said input circuit to the output dead-end resistance through successive tubes including an increasing number of sections of both of said filters, and the carrier frequency of said system being located at the mid-frequency of said pass band, whereby the total phase displacement through successive tubes from said input circuit to said dead-end resistance at said carrier frequencies differs by 180 degrees so that the carrier-frequency power therein tends to cancel out.
9. In a modulated-carrier signal-translating system, a signal-translating channel including input and output circuits, input and output dead-end filters, a plurality of vacuum tube modulators effectively in parallel and coupling said circuits through portions of said filters, one of said filters being of a low-pass type and the other of said filters being of a band-pass type, said filters having pass bands of equal width, each of said filters having a dead-end resistance termination, said tubes being respectively coupled to said filters at electrically spaced junctions thereof remote from said dead ends, said input and output circuits being coupled with the respective filters at junctions of said filters more remote from said dead ends than said junctions to which said tubes are coupled, whereby the respective paths from said input to said output circuits through successive tubes include an increasing number of sections of one of said filters and a decreasing number of sections of the other of said filters, the respective paths from said input circuit to said output dead-end resistance through successive tubes including an increasing number of sections of both of said filters, and a source of carrier frequency voltage coupled through said input circuit to said tubes in such phase as to be cou-
- the respective filters at junctions of said filters more remote from said dead ends than the said junctions to which said tubes are coupled, whereby the respective paths from said input to said output circuits through successive tubes include increasing numbers of sections of one of said filters and decreasing numbers of sections of the other filter, the respective paths from said input circuit to said output dead-end resistance through successive tubes including an increased number of sections of both of said filters, and said junctions being displaced along each filter by a portion having zero to 180 degrees phase shift over the pass band of said system, whereby the total phase shift from said input circuit to said output circuit through successive tubes has the same average value over said pass band.
10. In a modulated-carrier signal-translating system, a signal-translating channel including input and output circuits, input and output dead-end filters, a plurality of modulator vacuum tubes effectively in parallel and coupling said circuits through portions of said filters, said input filter being of a low-pass type and said output filter being of a band-pass type, said filters having pass bands of equal width, each of said filters having a dead-end resistance termination, said tubes being connected with said filter at electrically spaced junctions thereof remote from said dead ends, said input and output circuits being respectively coupled with said filters at junctions of said filters more remote from said dead ends than said junctions to which said tubes are coupled, whereby the respective paths from said input to said output circuits through successive tubes include an increasing number of sections of one of said filters and a decreasing number of sections of the other of said filters, the respective paths from said input circuit to the dead end of said output filter through successive tubes including an increasing number of sections of both of said filters, and a carrier-frequency circuit coupled to input circuits of said tubes with such relative phase as to be coupled through each tube to said output circuit in the same phase, the frequency of said voltage being located within the pass band of said band-pass filter.
11. In a modulated-carrier signal-translating system, a signal-translating channel including input and output circuits, input and output dead-end filters, a plurality of modulator vacuum tubes effectively coupling said circuits through portions of said filters, said input filter being of a low-pass type and said output filter being of a band-pass type, said filters having pass bands of equal width, each of said filters having a dead-end resistance termination, said tubes being respectively connected to said filters at electrically spaced junctions thereof remote from said dead ends, said input and output circuits being coupled with the respective filters at junctions of said filters more remote from said dead ends than said junctions to which said tubes are coupled, whereby the respective paths from said input to said output circuits through successive tubes include an increasing number of sections of one of said filters and a decreasing number of sections of the other of said filters, the respective paths from said input circuit to said output dead-end resistance through successive tubes including an increasing number of sections of both of said filters, and a source of carrier frequency voltage coupled through said input circuit to said tubes in such phase as to be cou-

pled through each tube to said output circuit in the same phase, the frequency of said voltage being located at one edge and just within the pass band of said output filter, whereby the 5 band-pass output filter passes all of one side-band corresponding to all modulation frequencies of the band of said low-pass input filter.

12. In a modulated-carrier signal-translating system, a signal-translating channel including a 10 plurality of phase-displaced input circuits and an output circuit, a coupling network comprising a dead-end filter having a resistance termination at said dead end, said input circuits being coupled with said filter at electrically spaced junctions 15 thereof remote from said dead end, and said output circuit being coupled to said filter at a point more remote from its dead end than said junctions, whereby respective paths through said successive input circuits to said output circuit include a decreasing number of sections of said filter and successive paths from said input circuits to said output dead-end resistance include an increasing number of sections of said filter, and the carrier frequency being located within the 20 pass band of said filter and so related to the transfer characteristics of said filter that minimum power is dissipated in said dead-end resistance termination.

13. In a modulated-carrier signal-translating system, a signal-translating channel including a 30 plurality of phase-displaced input circuits and an output circuit, a coupling network comprising a dead-end filter having a resistance termination at said dead end, each of said input and output 35 circuits being coupled with said filter at a junction of said filter separated from said dead end by at least one half-section of said filter, said input circuits being coupled with said filter at electrically spaced junctions thereof and said 40 output circuit being coupled to said filter at a

point more remote from its dead end than said junctions, whereby respective paths through successive input circuits to said output circuit include a decreasing number of sections of said filter, and successive paths from said input circuits to said output dead-end resistance include an increasing number of sections of said filter, and the carrier frequency being located within the 5 pass band of said filter and so related to the transfer characteristics of said filter that 10 minimum power is dissipated in said dead-end resistance termination.

14. In a modulated-carrier signal-translating system, a signal-translating channel including a 15 plurality of phase-displaced input circuits and an output circuit, a coupling network comprising a dead-end filter having a resistance termination at said dead end, a plurality of vacuum tubes having output capacitance, each of said input circuits being coupled with said filter through 20 one of said vacuum tubes at electrically spaced junctions thereof remote from said dead end, the said output capacitance of each tube comprising a substantial part of a shunt arm of said filter at the junction at which the particular vacuum 25 tube is coupled, said output circuit being coupled to said filter at a point more remote from its dead end than said junctions, whereby respective paths through successive input circuits to said output circuit include a decreasing number of 30 sections of said filter and successive paths from said input circuits to said output dead-end resistance include an increasing number of sections of said filter, and the carrier frequency being 35 located within the pass band of said filter and so related to the transfer characteristics of said filter that minimum power is dissipated in said dead-end resistance termination.
